UNITED STATES PATENT OFFICE.

ROBERT GOW REID, ARTHUR BATES, AND FRED RICKS, OF LEICESTER, ENGLAND,
ASSIGNORS TO UNITED SHOE MACHINERY CORPORATION, OF PATERSON, NEW JER-
SEY, A CORPORATION OF NEW JERSEY.

MACHINE FOR SEWING LEATHER BAGS OR SIMILAR ARTICLES.

Application filed October 15, 1921, Serial No. 507,968, and in Great Britain October 20, 1920.

The present invention relates particularly to apparatus for sewing the end portions into the body or lid of bags such as attaché cases and suit cases,—articles usually composed of leather or of compressed fibrous material such as leather-board, straw-board, and the like.

The object of the present invention is to provide improved means for performing the sewing operation above referred to whereby better work can be produced with considerable reduction in the amount of skill and manual labor required.

With this object in view, the present invention consists in combining with the stitch-forming devices of a curved hook needle sewing machine improved forms of work support and guides hereinafter described and claimed.

20 Referring to the drawings:

Fig. 1 shows, in perspective, a machine according to the invention arranged for the sewing of bags and like articles;

25 Figs. 2, 3 and 4 show various types of forms for internally supporting the work, the latter figure showing a bag supported on the form;

30 Fig. 5 shows, partly in section, a view, at right angles to Fig. 4, of a portion of a bag form as shown in Fig. 4 but adapted for use with metal framed bags and with a bag thereon;

35 Fig. 6 shows an extensible bag form end-piece;

Figs. 7 and 8 are detailed sectional views 30 of portions of construction of bag forms for use in sewing bag lids and shown with a bag thereon;

40 Fig. 9 shows, in perspective, a type of sewing machine bag support alternative to that shown on the machine in Fig. 1;

Fig. 10 is an elevation of the same; and

45 Fig. 11 is a section on the line A—A of Fig. 10;

Figs. 12 and 13 are views of an external support for the bag additional to that provided at the sewing point.

For the purposes of explanation, it will 50 be assumed that the operation to be performed by the apparatus illustrated in the drawings is the sewing together at the ends of the lid or body of a suit case or attaché case of a sheet of the material which is

bent to form the top of the lid or the bottom of the body and the front and back of the lid or body with two flat sheets which form the ends of the lid or body.

This operation is effected by a lockstitch seam extending along the perpendicularly abutting or mitred edges of the sheet with its stitches lying in a plane at an angle of about 45° to the planes of the respective sheets.

As these abutting edges, which usually are merely basted or otherwise temporarily secured together, are struck slantingly by the awl and needle (the machine illustrated being a curved awl, curved hook needle machine of well-known type) they should be supported internally to maintain them in proper relative and absolute position so that when the stitches have been set in the case of perpendicularly abutting edges the plane of the raw edge or edge face of the lid or body portion and the plane of the surface of the end portion or sheet sewn thereto will coincide, and in the case of mitred edge work the two mitred edges will abut properly, and to ensure the line of the seam being at the correct distance from the edge (and straight) on the respective surfaces.

According to one feature of the invention this result is attained by providing a form which, introduced into the bag in a collapsed state, is expanded to fill out the bag and support rigidly, and it may be placed, the abutting edges in proper relation for the sewing.

The expansion may occur only in one direction, in which case the desired result may be attained by the employment of a structure as shown in Fig. 2 comprising two flat rectangular boards 10 of the internal length of the bag and as wide as the bag is deep, each hinged at 11 (on an axis extending along and near to the inner widthwise edge of the end face of the board) to the end of an end board 12 (of the same width as the others and of a length sufficient to place the outer faces of the boards 10 at a distance apart equal to the internal width of the bag) divided centrally and hinged at 13 on an axis parallel to that of the other hinges so that on collapsing these end boards the structure may be readily introduced into and removed from the bag. A

strut may be provided, its ends sliding into grooves 14 in opposite boards of the expanded form, to lock the form in expanded condition.

- 5 Alternatively for some classes of work, a simple form as shown in Fig. 3 will suffice; in this construction the end boards 15 are rebated at 16 at their ends at a slight angle to the vertical and side boards 17 are used 10 therewith having their ends cut to a corresponding angle. It will be evident that, the end boards having been placed within a bag, insertion of the side boards with their ends against the rebated portions 16 will force 15 apart the end boards. The side boards 17 may conveniently be made as shown of lesser height than the end boards so that articles that differ slightly in length may be properly expanded by varying the amount by which 20 the side boards are pushed down without the top edge of the latter projecting above the top of the bag body so as to hamper sewing of the bag lid with the latter closed upon the body.
- 25 It is preferable, however, that the form be expansible in two directions and further that the expansion and contraction be not only such as to facilitate the introduction of the form into and its removal from the bag 30 but be capable of dealing say with departures of the dimensions of the bag from a reputed dimension or it may be with different sizes of a range.

To deal with this, the form may be constructed as shown in Fig. 4, comprising four units 18 each made up of two flat rectangular boards of a width equal to the depth of the bag and secured together permanently and rigidly at right angles by the fillets 19 40 to constitute corner forms, each unit comprising a board somewhat less than half the length of the long side and a board somewhat less than half the length of the short side of the bag, so that the four units 45 appropriately placed together and with their adjacent ends somewhat spaced apart constitute a complete frame-like internal support for the bag.

50 Units of this type when placed in the bag may be appropriately expanded simultaneously laterally and longitudinally by an extensible connector joining the central pivots of a pair of toggles each pivoted at one end to the angular corner of one of the units. It 55 is in many cases desirable, in the interests of simplicity and convenience of nesting of the units for storage to have the units readily separable, and also to avoid complexity of mechanism; and a structure having these 60 properties may be obtained by merely wedging the units apart by strut boards extending across the bag and having wedge formations on their ends which force these apart, it being for instance sufficient as shown in 65 Fig. 4 to provide one strut board 20 extend-

ing widthwise of the bag and two short ones 21, 22 extending in line from the middle of the strut board 20.

The ends of these strut boards have wedge faced ends 23 extending at an angle height- 70 wise of the bag to engage abutments 24 upon the units as shown also in dotted lines in Fig. 5.

A form of the nature hereinbefore described with reference to Fig. 3 may be made 75 expansible in both directions by means of expanding end pieces of which one is shown in Fig. 6. In this construction the end piece is divided vertically into two halves 26, 27, connected by two metal bars 28 and 29. 80 The bar 28 (fast to the part 26) lies in a recess cut in the halves of the end piece and has pivoted upon it a handled lever 30 formed around its lower portion as a pinion 31 to engage a rack 32 cut in the bar 29 85 which is fastened to the part 27 and lies upon the face of the end piece. Two overlying struts 33 provide guideways for the bar 29 and hold the bar 28 in its recess. The two halves 26 and 27 of the end piece may be ex- 90 panded to fit the work by actuation of the lever 30 and thus forcing the parts to the right and left respectively. The parts may be locked in adjusted position by a pin 34 which can be thrust through a hole 35, in the lever 30, into any one of a series of holes 36 in the bar 28 with which the hole 35 is 95 brought into register.

A thin angle plate 37, shown as attached 100 to the part 26, may be fixed to one of the halves of the end pieces to provide, independently of expansion, a continuous rear lower edge and consequent continuous abutment for the sewing operation along this edge. 105

This construction has been described as an end piece; it may also be employed if desired for the side pieces of a form and it will be understood that a device as shown in Fig. 6 lends itself to use with side pieces 110 of different lengths to deal with different sizes of bags of a range.

While for larger bags in which the lid and body are completed separately and the body is not only of considerably greater depth 115 than the lid but the units 18 have to be tapered somewhat near their top edges as shown in Fig. 5 to conform to the tapered structure usually given to the mouths of such bags to facilitate the closing down of the lid, and in which these units have to be of less depth than the bag (as also shown in Fig. 5) to allow of their being placed in position under the iron frame 25 which generally runs around the mouth of the bag, 120 it is preferable to have distinct adjustable forms for the lid and the bag respectively, yet for smaller bags such as small attaché cases in which the lid and body are completed while joined together the same form 125

may be used for the sewing of both parts by making, as shown in Fig. 7, those boards 38 of the form which run along the ends of the bag somewhat wider than the depth of the bag and providing thereon a thin bead 39 projecting over the top edge of the end pieces 40 of the body of the bag by an amount slightly greater than the thickness of the material of the end pieces so that, in the first operation of the sewing of the lid 41 with the lid shut down on the body portion (containing the form), this bead may snugly enter the corner formed by the end and top of the lid and rigidly support these portions in correct relation at the very corner. A similar result may be secured by the construction shown in Fig. 8. In this case short studs 42 are provided on the top of the end pieces 38 of the form in order to position a thin strip of metal 43 of right angle cross section placed along the top of the end pieces so that one portion of the strip is seated thereon, the studs 42 entering appropriate holes in this portion, and the portion 44 perpendicular thereto extends between the end portion 45 of the lid and the end portion 40 of the body, and being of width equal to the width of the end portion of the lid and of a length equal to that of this portion of the lid not only positions relatively the top and end of the lid but the ends of the end of the lid and the ends of the front and back of the lid.

The bag to be sewn with the form expanded in it is preferably sewn on a machine (as illustrated in Fig. 1) of the well-known construction used in the stitching of outsoles of boots and shoes and features of the construction of which are described in the specification of United States Letters Patent No. 473,870, dated April 26, 1892. To fit the machine for this work the thread-lock and the devices which vary the length of thread supplied in accordance with the variation in thickness of the work are removed so that the machine operates with the tension device controlling stitch-setting and thread supply.

At the sewing point a work-guide or support 1 is provided which is formed of a plate having two plane surfaces 2 and 3. The portions of the work support provided with the surfaces 2 and 3 are arranged at right angles to each other and form abutments which are rigidly and immovably secured to each other and thus support and guide the work in an accurate and reliable manner and cause the stitching to be located at the exact predetermined position on both external surfaces of the work. The edge common to these surfaces lies along the line of feed, approximately in the same horizontal plane as the locks of the stitches of the seam and at a distance from the centre of oscillation of the needle somewhat less than the radius of the latter, the surfaces being perpendicular the one to the other and usually at some 45° to the horizontal. The surface 3 is much longer (along the line of feed) than it is wide, being, say, some five or six inches long and hardly more than two inches, if that, in width, so as to give ample support against tipping of the work about an axis extending from front to back of the machine and also (by avoiding undue width) render practicable the sewing of work which within some two inches of the edge has some projecting fitting.

In each surface of the support there is formed a slot to allow of the passage of the awl and needle, 4 denoting the slot in the upper surface of the support and 5 that in the lower. These slots are made just wide enough to allow of the maximum feed by the awl of the work, the awl perforating the work towards the right side of the slots into the lower of which it enters first, and the plane of operation of the needle lying to the extreme left of the slots. The needle enters by the slot 4 and emerges, to have the needle thread looped on it, by the lower slot 5. As will be seen by reference to Fig. 9 which shows another work support of similar general type on a larger scale the slot 4 is preferably wider at its left side than at its right; this is due to the needle's passing through the support in such a way as to require greater clearance than the awl in this particular opening of the support. The slots extend no further towards the said common edge than is just necessary to allow the needle and awl to operate through the plate in the various conditions of adjustment of the plate likely to be requisite, it being desirable to leave between the slots as wide an angular channel of metal as is practicable so that at the points where the needle and awl enter and leave the work each surface of the work may be furnished with an abutment surface on the plate at all sides of the path of the needle or awl. This reduces the likelihood of unsatisfactory results being obtained through the material of the bag being forced or pulled away from the form by the tool passing into it.

The work support shown in Fig. 1 is suitable for mitred edge work, that is where the abutting edges of the bag sides and ends are each bevelled off to about 45° ; for "solid edged" work, however, that is work in which, as hereinbefore indicated, the edge of the bag ends abuts perpendicularly against the inner surface of the sheet forming the bag sides, a work support of the form shown in Figs. 9, 10 and 11 may be used, in which the surface of the lower and larger portion 3 of the work support has a shallow groove 6 milled to allow the work to be seated firmly on the support even should the materials thereof at their abutting edges be somewhat

rough or irregular or, cut slightly on the bias, it is convenient to form that section of the groove which extends beyond the sewing point considered along the line of feed somewhat wider than the other portion since it is desirable that neither portion should be wider than is absolutely necessary and the setting of the stitches tends to throw up a bead or bulge at the margin of the sheets 10 of the workpiece by pinching these materials together just a little distance from the free edges.

In addition, the actual stitching itself usually projects slightly from the surface 15 of the work, and this groove avoids marring of the surface of the thread on the work after passing the sewing point.

This form of work support also enables the bodies of attaché cases and similar articles which have the top or top and back 20 portions of the lid in one piece with the bottom and back of the body of the bag to be sewn, clearance being provided for the increase in width of this sheet at that portion of it where from forming the back of 25 the bag it changes its function to become the back of the lid or the top of the lid. The operation of sewing the bag body will start at that corner of the bag end adjacent the 30 lid as one end of the article is being sewn and will stop at the similar corner when the other end is being sewn. In the former case the edge of the lid top or lid back is accommodated in the recess 7 to the left of the 35 needle for the first few stitches, passing out to the left as the sewing proceeds; in the latter case as the last few stitches are being put in, the lid top or lid back enters the recess 8 to the right of the needle it being 40 understood that the lid end-pieces are not present at this stage. The upper surface of the work support is continued into the angle at the projection 9 between the recesses to provide a solid abutment for the work to be 45 held against during the whole of the sewing operation.

To provide for adjustments a work supporting plate either of the form shown in Fig. 1 or of that shown in Figs. 9, 10 and 11 50 may be conveniently supported on the machine by a bracket 50 fastened to the under side of that portion of the frame in which the shuttle is mounted in a machine according to the specification above mentioned and 55 at the place thereon where in boot and shoe sewing the work table is mounted. This bracket 50 is fastened to the frame by screws passing through slots 51 in it to allow of forward and rearward adjustment along the 60 plane of the surface 3 and also has two further slots 52, 53 by which screws 54 connect it to a slotted lug 55 upon the lower plane of the work support so that adjustment may be effected in the plane of the surface 2 and 65 also (by virtue of the crossing slots in the

parts 50, 55) about a horizontal axis parallel to the feed line. Additional support is provided by an arm 56 on the left side of the plate which is clamped to the frame by that bolt which in boot and shoe work is the 70 pivot for the presser foot lever and in this case passes through an enlarged opening in the arm.

This arrangement also allows of adjustment of the work support horizontally forwardly and backwardly relatively to the needle and awl centre so that the distance of the stitching as a whole from the extreme edge of the work may be set as desired. By tilting the support about a horizontal axis, as is permitted by the adjusting means, the relative distances of the stitching from the work edge on the two external faces of the work, that is, the angle of the stitching through the work, can be readily 85 varied.

In some classes of work it has been found that if the awl and needle are set and operated in the usual manner, that "burring" is apt to be produced by the pushing up or 90 out by the awl of small portions of the material of the article being sewn, and the penetration of the needle, through from the opposite side to that of the awl, does not always remedy such displacement, an inferior appearance of work then resulting. To avoid such a difficulty, the awl may be shortened so as to complete its piercing of the work just short of the further surface 95 thereof, and the needle may be sharpened so as easily to pierce the small remaining thickness of the work and then to traverse the awl hole.

An adjustable auxiliary support for the work is preferably provided and conveniently this is connected to the machine column; as shown in Figs. 12 and 13 it may be similar in general form to that located at the sewing point but the angular plate 60 of which it is formed is considerably 100 longer than that constituting the support at the sewing point and is positioned to engage the materials at those portions of the body or lid which correspond to those which at the other end of the article are at that time being 105 sewn together. For this purpose one surface of the auxiliary support is positioned in the same plane as the lower surface 3 of the support at the sewing point and the plane of the needle bisects the length of 110 each support.

The auxiliary support will usually require no adjustment in the course of the sewing operations on a body portion or lid where these are separately sewn (as the article is 115 usually sewn only along a margin at all its parts equidistant from the margin resting on the angular plate 60) but will require adjustment when the angular position of the support at the sewing point is varied and as 120 125 130

the work dimensions are changed. For this purpose the auxiliary support is conveniently provided with a slotted lug 61 at each end extending perpendicularly to its work supporting surfaces each lug being connected to a corresponding bar 62, extending from the machine column, by a clamping bolt 63 passing through the slot in the lug and a slot in the bar.

10 In some classes of work where the weight of the articles sewn is not great the auxiliary support may be merely a plane surface aligned with the plane of the portion 2 of the sewing point work support, and in such

15 case may take the form of a board mounted upon a column and adapted to be raised and lowered and also to be turned about a horizontal axis and be duly locked in adjusted position on the column.

20 The sewing machine is preferably provided with a clutch adapted to stop the machine invariably at the same point in its cycle of operations, that is to say with the needle and awl both clear of the work as shown in

25 Fig. 1. This is desirable, as at the beginning and end of the seam at the corners of the body and lid of the bag it is customary to form a double stitch which requires that the operator, if he is to do the same thing

30 by machine, shall frequently stop the machine to reposition the work for the repetition of the stitch so that the awl shall enter once more a hole just previously made by it. As the article may be heavy or awkward to

35 hold with one hand only, it is undesirable that he should have to use one of his hands to turn the hand wheel of the machine to free the work from the awl or needle for the repositioning, and, moreover, time is lost as

40 his attention is diverted from the mere repositioning of the work. Again, should the machine stop with the needle or awl in the work, a serious strain might come upon one or other of these tools if the operator letting

45 go of a heavy bag with one hand to rotate the mainshaft with that hand lost control of the work and its weight came suddenly upon the tool. A convenient clutch for this purpose is that described in the specification

50 of British Letters Patent No. 720C of 1907.

A clutch of this type is shown in Fig. 1, the pendant lever R⁴ being oscillated by the swash ring described in that specification while the clutch is engaged, and being stopped to disengage the clutch at a definite spot in its oscillation through the toggle members R⁵ and R⁷ following release by the operator of the pedal connected to the rod R⁸.

60 The nature and scope of the invention having been indicated and apparatus embodying the several features of the invention in their preferred form having been specifically described, what is claimed is:

65 1. A machine for sewing leather bags or

stitch-forming devices including a curved hook needle, and a work support comprising abutments rigidly and immovably secured to each other and provided with work supporting surfaces substantially at right angles to each other and extending in the direction of feed, arranged to position the corner formed by a side and end of a bag in the path of the needle.

2. A machine for sewing leather bags or similar articles having, in combination, stitch-forming devices including a curved hook needle, a work support comprising abutments rigidly and immovably secured to each other and provided with surfaces substantially at right angles to each other and extending in the direction of feed to support externally the side and end of a bag and an expansible form supporting internally the side and end of the bag and cooperating with said surfaces to position the corner formed by the side and end of the bag in the path of the needle.

3. A machine for sewing leather bags or similar articles having, in combination, stitch-forming devices including a curved hook needle, a work support comprising rigidly connected abutments rigidly and immovably secured to each other provided with work supporting surfaces substantially at right angles to each other and extending in the direction of feed, and means permitting an angular adjustment of the work support to vary the angle of the stitching through the work.

4. A machine for sewing leather bags or similar articles having, in combination, stitch-forming devices including a curved hook needle, a work support comprising rigidly connected abutments rigidly and immovably secured to each other provided with work supporting surfaces substantially at right angles to each other and extending in the direction of feed, and means permitting an adjustment of the work support to vary the distance of the stitching as a whole from the extreme edge of the work.

5. A machine for sewing leather bags or similar articles having, in combination, stitch-forming devices including a curved hook needle, a work support comprising rigidly connected abutments rigidly and immovably secured to each other provided with work supporting surfaces substantially at right angles to each other and extending in the direction of feed, and means permitting an adjustment of the work support to vary the relative distances of the stitching from the edge on the two external surfaces of the work.

6. A machine for sewing leather bags or similar articles having, in combination, stitch-forming devices including a curved hook needle, a work support comprising rig-

idly connected abutments provided with work supporting surfaces substantially at right angles to each other and extending in the direction of feed, and also provided with 5 a needle opening and with a lid-receiving recess at each side of the needle opening to permit sewing of the body with the lid portion in place thereon.

7. A machine for sewing leather bags or 10 similar articles having, in combination, stitch-forming devices including a curved

hook needle, a work support comprising rigidly connected abutments provided with work supporting surfaces substantially at right angles to each other and extending in 15 the direction of feed, and also provided with a groove to receive the edge portion of the work.
